UNITED STATES PATENT OFFICE.

ALVIN NELSON WOODARD, OF MANSFIELD, OHIO, ASSIGNOR OF ONE-HALF
TO ABRAHAM SMALL, OF SAME PLACE.

DESIGN FOR A PEN-GUARD.

SPECIFICATION forming part of Design No. 26,379, dated December 8, 1896.

Application filed October 28, 1896. Serial No. 610,372. Term of patent 14 years.

To all whom it may concern:

Be it known that I, ALVIN NELSON WOODARD, a citizen of the United States, residing at Mansfield, in the county of Richland and State of Ohio, have invented and produced a certain new and original Design for Guards for Penholders; and I do declare the following to be a full, clear, and exact description of the invention, such as will enable others skilled in the art to which it appertains to make and use the same.

My invention has relation to a new and original design for a guard for penholders. It relates to the entire configuration of the guard, and especially to a guard constructed of spring sheet metal.

My invention relates particularly to a guard for penholders, as illustrated in the accompanying drawings, in which—

Figure 1 is a perspective view of a guard for penholders embodying my design. Fig.

2 is an end view of the same. Fig. 3 is a plan view of the same, and Fig. 4 is a perspective view of a penholder with the guard in position.

1 represents the cylindrical body, having 25 contiguous parallel edges 2 2, and 3 3 are the integral wings elliptical in shape and extending at a right angle on opposite sides of one end of the cylindrical body, as shown in the drawings.

Having thus fully described my design, what I claim as new and original, and desire to secure by Letters Patent of the United States, is—

The design for a penholder-guard, substantially as herein shown and described.

In testimony whereof I hereunto affix my signature in presence of two witnesses.

ALVIN NELSON WOODARD.
